(57) **CLAIM**

The ornamental design for a manifold as shown and
described.

DESCRIPTION

FIG. 1 is an upper perspective view of a first design of a
manifold;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1;

FIG. 8 is a lower perspective view of the design of FIG. 1;

FIG. 9 is a first perspective view of the first design of a
manifold with an alternate flange connection;

FIG. 10 is a second perspective view of the first design of a
manifold with the alternate flange connection of FIG. 9;

FIG. 11 is an upper perspective view of a second design of
a manifold;

FIG. 12 is a front view of the design of FIG. 11;

FIG. 13 is a rear view of the design of FIG. 11;

FIG. 14 is a first side view of the design of FIG. 11;

FIG. 15 is a second side view of the design of FIG. 11;

FIG. 16 is a top view of the design of FIG. 11;

FIG. 17 is a bottom view of the design of FIG. 11; and,

FIG. 18 is a lower perspective view of the design of FIG. 11.
The broken lines shown in the drawings are included for the
purpose of illustrating the unclaimed boundary and
unclaimed portions of the manifold. The broken lines form
no part of the claimed design.

1 Claim, 18 Drawing Sheets
